UNITED STATES PATENT OFFICE.

GEORGE D. MATCHAM, OF PITTSFIELD, OHIO.

SCRAPER.

SPECIFICATION forming part of Letters Patent No. 234,834, dated November 23, 1880.

Application filed July 3, 1880. (Model.)

To all whom it may concern:

Be it known that I, GEORGE D. MATCHAM, of Pittsfield, in the county of Lorain and State of Ohio, have invented new and useful Improvements in Road-Scrapers, of which the following is a description, reference being had to the accompanying drawings, making a part of this specification, in which—

Figure 1 is a side view of the scraper in position for being loaded. Fig. 2 is a side view of the same when dumped. Fig. 3 is a rack, to which reference will be made. Fig. 4 is a plan view. Figs. 5 and 6 are detached sections.

Like letters of reference refer to like parts in the several views.

This invention relates to a self loading and discharging dirt-scraper, a full and complete description of which is as follows:

In the drawings, A represents the body of the scraper, which consists of the sides B, bottom C, and back D, all of which is like scrapers in ordinary use.

The edge of the scraper is metal, and consists of an upper plate, a, the edge of which is the cutting-edge. The upper edge of the plate is flush with the bottom of the scraper to prevent lodgment of dirt at the junction of the plate and bottom. Said plate is secured to the wood-work of the scraper by the straps 25 E, riveted to the plate and bolted to the edge of the sides B. For further security a plate, b, is attached to the under side of plate a. The rear edge of plate b is secured to the scraper by straps F, riveted to the plate and bolted to 30 the edge of the sides B, substantially as shown in the drawings.

To each side of the scraper is fixed a draft-plate, G, Figs. 1 and 4, to which the arms H are respectively pivoted by check-stirrups I. 40 Said stirrup consists of a rod having one end turned at right angles and inserted loosely through the arm into the scraper, and secured therein by any suitable means. A portion of said rod is turned into a loop, c, Fig. 5, and 45 then bent parallel to the opposite end and secured in the side of the scraper, as seen in said figure. The purpose of the check-stirrup will presently be shown.

To the back of the scraper is secured a segmental rack, J, arranged to engage a rack, K, projecting from the under side of the stay-bar

L, pivoted in the standards M, and extending therefrom back to the segmental rack, as seen in Fig. 1. Said rack K is pivoted at a' in the bar, a slot being made therein for its admission, and wherein it is moved upward and downward by the handle N, for engaging and disengaging it from the segmental rack alluded to.

O, Figs. 1 and 4, is a guide for holding from lateral movement the end of the bar L. Said guide is pivoted to the segmental rack and allowed a movement in alignment with the bar.

P is a cross-piece, on which the arms H rest, and are secured thereto by strap-bolts g, which 65 are adjustable in slots c', Fig. 4. To the cross-piece alluded to is secured the tongue R, to the under side of which are pivoted the ends of the arms H. To the upper side of the tongue is attached the evener A' of the double-tree 70 by means of the slotted hammer-strap S, in the slot of which the hammer-bolt is inserted. A corresponding slot is made in the tongue through which the bolt passes and slides therein, as and for a purpose presently shown. 75

Between the standards M is fixed to the tongue R a stud, e, to which is pivoted a dumping-arm, B'. Said arm is attached to the evener A' by a rod, i, provided with a hook, whereby it is hooked into a staple of the evener. The 80 opposite end of the rod is pivoted to the arm B' at n. A draft-chain, C', connects the back of the scraper to the stud e, and a dumping-chain, D', connects the arm B' to the chain C', as shown in Fig. 1. 85

E' is a yoke, the upper part of which is around the bar L, whereas the lower part of the yoke is around the dumping-arm, for lifting said arm when it is in the position shown in Fig. 1. 90

Having described the construction of the scraper and the devices for operating the same, the practical operation thereof is as follows: The position of the machine, as shown in Fig. 1, is such as, when ready for scraping in this position, it will be seen that the check-bar L is locked by the rack K to the segmental rack J, and in which engagement it is held by a yoke, m', attached to the end of the bar and thrown up over the handle N of the rack, 100 thereby retaining the rack below the under side of the bar, that it may engage the seg-

ment J. By this engagement of the two racks the scraper cannot turn over while being used, the check-bar and rack holding it firmly in position while being used and filling for dumping.

The draft in pulling forward the scraper is exerted, mainly, upon the rod i, dumping-arm, and chain C', there being at this time but little draft upon the dumping-chain D', as the line of draft is very near the pivotal point n'. In order to dump the scraper the operator lifts the check-bar from its engagement with the rack J. The scraper, when released from the check, will be pulled over to the position shown in Fig. 2 by the dumping-arm, which, on lifting the check-bar, causes the yoke E' to lift upward the dumping-arm, thereby bringing the points n and n' so far above the pivotal point c' of the arm that it is easily and readily drawn forward from the position shown in Fig. 1 to that shown in Fig. 2, and at the same time draws with it the scraper, by virtue of the chain D', by its connection with the chain C' and dumping-arm. In this act of turning or dumping the scraper the double-tree also moves forward by the hammer-bolt moving along in the hammer-strap, thereby pulling forward the arm for dumping the scraper.

It will be observed that the dumping-chain D' is attached to the extreme end of the dumping-arm at n', the link of the chain being held in the lower end of the slot; hence on lifting the arm the chain D' will be drawn rapidly upward as well as forward, thereby drawing upon the scraper in a lifting manner, as the end of the arm and the back of the scraper move upward and forward in the same direction and at the same time.

The operator can at any time check the dumping movement of the scraper by means of the bar, for the purpose of leveling the dirt with the edge of the scraper. To prevent the scraper from turning so far over as to strike upon the cross-piece P is the purpose of the stirrup I, against which the arms H impinge, as seen at r in Fig. 2, thereby retaining the scraper in the position seen in said Fig. 2.

The edge of the scraper may be caused to scrape more or less deeply into the ground by shifting the connections of the arms therewith

nearer to or farther from the scraping-edge. The holes d' are made in the sides for that purpose. More or less angle can be given to the position of the scraper for scraping, or held in a vertical position for leveling dirt, by adjusting the check-bar in its engagement with the segment-rack J, as above described.

Scrapers of different widths can be used in connection with the dumping device by adapting the width of the arms to the scraper, which may be done by loosening the strap-bolts g, thereby allowing the arms to be spread out or closed in, as the width of the scraper may require.

Fig. 3, Plate 1, represents a rack, which may be secured to the under side of the check-bar in lieu of the rack K.

What I claim as my invention, and desire to secure by Letters Patent, is—

1. The combination of the scraper A with the segment-rack, check-bar, and adjustable rack K, pivoted therein, and standards M, substantially as described, and for the purpose set forth.

2. The dumping-arm B' and chains D' and C', in combination with the scraper, substantially as and for the purpose specified.

3. The sliding double-tree evener A', slotted hammer-strap and pole, bolt d, and rod i, in combination with the dumping-arm, substantially as and for the purpose set forth.

4. In combination with the check-bar L and dumping-arm, the yoke E', as and for the purpose specified.

5. In dirt-scrapers, the adjustable arms H and check-stirrups, in combination with the scraper, as described, and for the purpose specified.

6. The combination of the scraper, segmental rack, and rack K, pivoted in the bar L, yoke E', chains and dumping-arm, rod i, sliding evener, and adjustable arms H and check-stirrups, constructed and arranged as described, and for the purpose set forth.

In testimony whereof I affix my signature in presence of two witnesses.

GEORGE D. MATCHAM.
